CLAIM

The ornamental design for a combined towel and pillow with carrying strap, showing my new design.

DESCRIPTION

FIG. 1 is a front elevational view of a combined towel and pillow with carrying strap showing my new design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a front elevational view thereof, shown rolled up and secured by the carrying strap. The stippling is intended to represent a conventional towel fabric.
